THOMAS H. VAN DYKE, OF KANSAS CITY, MISSOURI.

VARIABLE-STROKE OPERATING MECHANISM FOR ENGINES.

1,307,167.

Specification of Letters Patent. Patented June 17, 1919.

Application filed March 18, 1919. Serial No. 283,365.

To all whom it may concern:

Be it known that I, THOMAS H. VAN DYKE, a citizen of the United States, residing at Kansas City, in the county of Jackson 5 and State of Missouri, have invented a certain new and useful Improvement in Variable-Stroke Operating Mechanism for Engines, of which the following is a specification.

10 My invention relates to improvements in explosive engines.

One of the objects of my invention is to provide novel means for connecting the crank shaft and connecting rod of an explosive 15 engine by which the piston during the initial part of its outstroke and the latter part of its instroke travels at a greater rate of speed than would be the case if the connecting rod were pivoted in the usual manner directly 20 to the crank shaft, thereby affording a maximum compression of the charge, and utilizing a maximum amount of the explosive force of the charge.

25 My invention provides further a simple construction, which is cheap to manufacture, easily assembled, not liable to excessive wear, and which is durable and not liable to get out of order.

30 The novel features of my invention are hereinafter fully described and claimed.

In the accompanying drawing, which illustrates the preferred embodiment of my invention,

35 Figure 1 is a view partly in elevation and partly in longitudinal vertical section of a horizontal explosive engine provided with my improvement.

Fig. 2 is a top view of the same.

40 Fig. 3 is a diagrammatic representation of the path traveled by the pin which connects the connecting rod with the member which is pivoted to the crank shaft.

Similar reference characters designate 45 similar parts in the different views.

1 designates a reciprocative piston of an explosive engine 2 of the ordinary horizontal type and 3 the crank shaft provided with the usual crank 4.

5 designates a horizontal bar disposed at 50 the side of the shaft 3 which is distant from the piston 1 and which is mounted in upwardly and rearwardly extending bearings 6 on the engine base 7. 8 designates two levers pivoted on the bar 5 and pivoted by a 55 transverse pin 9 to one end of a connecting member 10, the other end of which is piv-

oted by a transverse pin 11 to the outer end of the usual connecting rod 12, which is pivoted in the usual manner to the piston 1.

The connecting member 10 has mounted 60 on it a bearing plate 13 between which and the connecting member is pivoted the crank 4. The crank 4 is pivoted to the member 10 intermediate of the pins 9 and 11 which constitute with the crank 4 three pivotal 65 points which are fixed relatively to each other.

By reason of the construction which has been described, the piston 1 travels faster during the initial part of its outstroke and 70 the latter part of its instroke than would be the case if the connecting rod 12 were pivoted in the usual manner directly to the crank 4. This permits utilizing to the fullest extent the explosive force of the charge, 75 and affords a maximum compression.

In the operation of the engine, when the charge is exploded the piston starts outward at high speed, thus preventing loss of power 80 by leakage and radiation or conduction away of heat. The piston 1 travels the full outstroke before the crank shaft 3 has made a half revolution. As shown in dotted lines in Fig. 1, the piston 1 has reached the outer limit of its stroke at the time the crank 4 85 has made only about one third of a revolution. During the instroke the piston travels slowly until near the latter part of the stroke at which time it travels more rapidly than if the connecting rod 12 were pivoted 90 directly to the crank 4. Thus when compression is high the piston 1 is traveling at a relatively high rate of speed, thus preventing the loss of pressure by leakage and thus greatly adding to the efficiency of the engine. 95 The piston travels the instroke during the time that the crank 4 is making the remaining two thirds of a revolution.

Owing to the speed of the piston on its outward stroke, the exploding charge does 100 not have time to lose much heat to the cylinder and piston and these parts do not become so highly heated as in the ordinary construction in which the connecting rod is connected directly to the crank. For these reasons 105 it is not necessary to employ a water jacket or other special cooling arrangement for the cylinder.

In Fig. 3 is a representation of the path of travel of the pin 11 during a revolution of 110 the crank shaft, the path being denoted by the line 14. The lines *a* and *b* designate on

the path 14 the two positions of the pin 11 shown in solid and dotted lines respectively in Fig. 1.

I do not limit my invention to the structure shown and described, as various modifications, within the scope of the appended claims, may be made without departing from the spirit of my invention.

What I claim is:—

- 10 1. In an explosive engine, the combination with a piston, connecting rod and crank shaft, of a lever pivoted at a fixed point, and a connecting member pivoted to the connecting rod and lever at two points fixed 15 relatively to each other, and pivoted to the crank shaft.
- 20 2. In an explosive engine, the combination with a piston, connecting rod and crank shaft, of a lever pivoted at a fixed point, and a connecting member pivoted to the connecting rod and lever at two points respectively which are fixed relatively to each other, and pivoted to the crank shaft intermediate of said two points.
- 25 3. In an explosive engine, the combination with a piston, connecting rod and crank shaft, of a lever pivoted at a fixed point located at the side of the crank shaft distant from the piston, and a connecting member 30 pivoted at three points, fixed relatively to each other, to the connecting rod, crank shaft and lever respectively; the pivotal connection of said member to said crank

shaft being intermediate of the other two pivotal connections of said member. 35

4. In an explosive engine, the combination with a piston, connecting rod and the crank shaft, of means connecting the crank of the crank shaft and connecting rod by which they are held a uniform distance 40 apart, and by which the piston completes its outstroke before the crank shaft has made a half a revolution.

5. In an explosive engine, the combination with a piston, connecting rod and 45 crank shaft, of means connecting the crank of the crank shaft and the connecting rod by which they are held a uniform distance apart and by which the piston during the initial part of its outstroke and during the 50 latter part of its instroke travels more rapidly than it would with the connecting rod pivoted directly to the crank.

6: In an explosive engine, the combination with a piston, connecting rod and crank 55 shaft, of means connecting the crank of the crank shaft and the connecting rod by which the piston during the initial part of its outstroke and the latter part of its instroke travels more rapidly than it would 60 with the connecting rod pivoted directly to the crank.

In testimony whereof I have signed my name to this specification.

THOMAS H. VAN DYKE.
